W. E. ELLIS.
FASTENER FOR SHOE UPPERS.
APPLICATION FILED JULY 26, 1907.

UNITED STATES PATENT OFFICE.

WARREN E. ELLIS, OF HAVERHILL, MASSACHUSETTS, ASSIGNOR TO ELLIS LACER COMPANY,
A CORPORATION OF MAINE.

FASTENER FOR SHOE-UPPERS.

No. 915,755.

Specification of Letters Patent. Patented March 23, 1909.

Application filed July 25, 1907. Serial No. 385,442.

To all whom it may concern:

Be it known that I, WARREN EUGENE ELLIS, a citizen of the United States, and a resident of Haverhill, in the county of Essex and State of Massachusetts, have invented certain new and useful Improvements in Fasteners for Shoe-Uppers, of which the following is a specification.

This invention relates to fasteners for temporarily securing together the eyeleted edges of shoe uppers during the process of lasting, and is herein represented as embodied in a fastener having the general construction shown and described in U. S. Letters Patent No. 653,929, granted July 17, 1900, to C. C. Harlow, being intended to improve upon the Harlow fastener in certain particulars which will hereinafter appear.

In the accompanying drawings, Figure 1 is a side elevation of a fastener embodying my invention; and Fig. 2 is a similar view showing a portion of a shoe upper with the fastener applied thereto.

The fastener illustrated in the drawings is like the one shown in the Letters Patent to Harlow above referred to in that it comprises a U-shaped body portion the arms of which are substantially parallel and are curved somewhat to conform to the top of a last, and in having the upper or outer arm 2 provided with a portion 3 which extends downward, or toward the inner or lower arm 4, in the same plane as the bend of the U, said portion 3 and the bend of the U providing eyelet-engaging members or shoulders which, when the fastener is inserted in a pair of opposite eyelets 5 as shown in Fig. 2, engage said eyelets and thus hold the sides 6 of the upper at the proper distance apart. In the Harlow fastener, however, the downwardly-bent portion on the upper or outer arm forms the extremity of said arm, while in my present fastener the corresponding portion 3 is located at a short distance from the extremity of the arm 2 and is doubled or folded upon itself to form the eyelet-engaging shoulder, the free end or extremity 7 of said arm 2 being bent away from the upper end of the doubled portion 3, as shown in Fig. 2, so that it lies on the outside of the upper when the fastener is inserted therein. Said end portion 7 is also, by preference, doubled or folded inward toward the portion 3, for the sake of giving a rounded finish to the end

of the fastener and thus preventing it from 55 defacing the shoe uppers.

To apply the fastener the inner arm 4 is inserted through one of a pair of opposite eyelets until said eyelet is located in the bend which connects the arms 2 and 4, and the portion 3 is then sprung into the opposite eyelet from the outer side of the upper, the fastener being thereafter held in place by the arm 4 when the parts are not under tension. In removing the fastener the portion 3 is 65 sprung out of its eyelet by engaging and lifting the terminal portion 7, which forms a species of handle which may be readily engaged by the operator or under which a suitable tool may be inserted for the purpose of 70 prying out the portion 3, and the capacity for being operated in this manner forms a distinctive and important feature of my improved fastener, practical experience with the fastener shown in the Harlow patent having demonstrated that the removal of that fastener involves considerable difficulty and inconvenience, inasmuch as there is no part of the fastener which can be quickly and conveniently engaged from the outside of the 80 upper for the purpose of lifting the outer arm and disengaging its downwardly-extending free end from the eyelet in which it is located. Furthermore, the presence of the terminal portion 7 in my fastener shows at a 85 glance at which end of the fastener the arm 2 is to be lifted, and thus does away with the necessity of providing this end of the fastener with a distinctive mark, such a mark being, at best, not easily discernible. 90

My fastener is usually made of a single piece of flat steel wire, and the inner arm 4 preferably extends a short distance beyond the downwardly-extending portion 3 and should have sufficient resiliency to cause it to bear against the lower end of said portion 3 when the parts are in their normal position. Said arm 4 may have any desired length, however, so long as the fastener is capable of being readily inserted and removed and of 100 retaining itself in operative relation to the eyelets.

I claim as my invention:

1. A detachable fastener for shoe uppers having inner and outer arms adapted to extend transversely between the eyeleted edges of a shoe upper and connected at one end by an eyelet-engaging bend, the outer arm being

provided near its free end with a doubled portion extending toward the free end portion of the inner arm and adapted to pass inward through an eyelet, and said doubled portion being extended at its outer end to provide a terminal portion adapted to be located on the outer side of the upper.

2. A detachable fastener for shoe uppers, having inner and outer arms adapted to extend transversely, one above the other, between the eyeleted edges of a shoe upper and connected at one end by an eyelet-engaging bend, the outer arm being provided near its free end with a doubled portion extending toward the free end portion of the inner arm and adapted to pass inward through an eyelet, and said doubled portion being extended at its outer end to provide a terminal portion adapted to be located on the outer side of the upper and having a folded-over extremity.

3. A detachable fastener for shoe uppers

composed of a single strip of spring metal bent to provide substantially parallel inner and outer arms connected at one end by an eyelet-engaging bend, the outer arm being provided near its free end with a doubled portion extending inward into contact with the inner arm, adjacent to the free end thereof, and adapted to be inserted into an eyelet from the other side of the upper, and said doubled portion being extended at its outer end to provide a terminal portion adapted to be located on the outer side of the upper and having a folded-over extremity.

In testimony whereof, I have hereunto subscribed my name this twenty-seventh day of May, 1907.

WARREN E. ELLIS.
